UNITED STATES PATENT OFFICE.

WILLIAM THOMAS JAMES, OF CHICAGO, ILLINOIS.

CONVEYER.

1,239,490.

Specification of Letters Patent. Patented Sept. 11, 1917.

Original application filed March 30, 1908, Serial No. 424,242. Divided and this application filed August 8, 1910. Serial No. 576,183.

To all whom it may concern:

Be it known that I, WILLIAM THOMAS JAMES, a citizen of the United States, residing at Chicago, in the county of Cook and State of Illinois, have invented certain new and useful Improvements in Conveyers, of which the following is a specification.

This invention has reference to the provision of an improved form of apparatus for handling coal or other like material in bulk, certain structures in which it is conveniently employed being shown in my co-pending application, Serial No. 424,242, filed March 30, 1908, of which this is a division. The invention has for its primary objects, the provision of an improved form of conveyer chain having buckets mounted therein, an improved form of stop device for affording a support for the bucket while it is in loaded position, and also acting as a stop for the movement of the bucket when it is tripped in dumping the material, and to provide an improved form of construction for tripping the bucket when traveling in a non-horizontal or vertical plane, which said trip device is constructed so that it can be thrown into and out of position at will—depending upon the place at which the bucket is intended to dump its contents.

A further object of the invention is the provision of a carrier chain of this general type, composed of link sections each having one bifurcated end and one single or plain end, and means for engaging said ends of the adjacent sections together, such link sections being provided with bucket-supporting means intermediate the ends.

The above, as well as such other objects as may hereinafter appear, I attain by means of a construction which I have illustrated in preferred form in the accompanying drawings, wherein—

Figure 1 shows in side elevation the upper end of a conveyer embodying my improvement;

Fig. 2 is another partial view in elevation, of the apparatus shown in Fig. 1;

Fig. 3 is a view of several of the buckets carried by the chain, shown as moving in vertical direction, with one of the buckets just dumped to discharge its contents;

Fig. 4 is another view of the apparatus shown in Fig. 3, showing it in a different elevation;

Fig. 5 is a view showing a slightly modified form of the dumping device, and

Fig. 6 is a view in elevation of the mechanism shown in Fig. 5.

Referring now more particularly to Figs. 1 to 4 inclusive, it will be seen that I have therein indicated a conveyer chain 7 arranged to be carried at its upper end by a suitable sprocket 8 mounted on a shaft 9 on the other end whereof is a similar sprocket carrying a similar chain or portion of conveyer belt, between which portions of the conveyer belt I mount a plurality of buckets 10 as shown, the same being adapted to travel in a path where the material is lifted vertically as indicated by the arrow in Fig. 3, and arranged to be dumped while the buckets are traveling in a vertical direction upward, as shown in said Fig. 3, into some suitable trough or other receptacle 11, by means of the tripping arrangement to be hereinafter more particularly described.

The side parts of the conveyer chain are composed of links indicated in Figs. 2, 4, and 6 particularly, such link members 13 having bifurcated upper ends at 14 and plain lower ends as indicated at 15, the plain ends being engaged within the bifurcated ends as shown, and the whole held together by suitable fastening bolts or other devices 16. Intermediate the ends of the link members 13 is a hub 17 through which extends the trunnion or support 18 which serves for carrying the bucket 10, there being a trunnion support at each end as shown, and each end of the bucket being provided with an angle-iron projection or bracket 19 preferably secured by rivets 20, with the flange 21 thereof extending laterally in position such as will engage with the trip roller 22 when the latter is in position for dumping the bucket, bringing the same into the position indicated in full lines in Fig. 3, in which the contents will be discharged into the trough 11 or any other suitable receptacle.

The trip roller 22 has a counterpart on the other side of the bucket, so that the brackets 19 will have simultaneous engagement on both sides of the bucket to take the strain better, and the rollers are carried upon the upper ends of rocker-arms 23 mounted on rocker-shafts 24, so that if desired, as indicated in Figs. 4 and 5, the rollers 22 can be simultaneously swung to the right out of

position where they will not engage the flanges 21 of the bracket device 19, and allow the buckets to pass without dumping, whereby if another trip device or pair of levers 23 carrying similar rollers 22 is mounted in another part of the path of movement of the buckets, the contents of the bucket can be dumped in such other position, as for example where it is required to distribute the contents of the buckets first in one horizontal plane and later in another higher horizontal plane as the bins or receptacles below become filled.

As a means for connecting together the two conveyer chains I provide a strap or connecting device 25, indicated more plainly perhaps in Fig. 4, and said strap 25 is secured to the side links as indicated at 26, whereby it holds the said side links in proper relative position, and also serves as a stop for the buckets 10, being so placed as to stop the buckets both in the loaded and in the unloaded position, as plainly indicated in the several figures.

This strap or connecting device 25 also serves to permit the bucket to right itself into operative position after having discharged its contents, the bucket being stopped in such vertical position by contact with the rear edge of the stop which, upon reference to Fig. 3, will be seen to be slightly inclined from the perpendicular.

Having thus described my invention and illustrated its use, what I claim as new and desire to secure by Letters Patent, is the following:

1. In a material handling apparatus in combination, a pair of opposing carriers each composed of a pair of chains, each comprising a plurality of link sections, means connecting the ends of adjacent sections together, a conveyer bucket pivotally mounted between the carriers, and means between the carriers adjacent said bucket for stopping the bucket in both its loaded and unloaded positions.

2. In a material handling apparatus, a pair of opposing carriers, a normally swinging conveyer bucket pivoted between said carriers, and means connecting said carriers together for stopping the bucket in both its loaded and unloaded position, said last mentioned means being so constructed as to permit the bucket to right itself into operative position after discharging its contents.

3. In a material handling apparatus, a pair of opposing carriers, a conveyer bucket pivotally mounted between said carriers, and a bar between the carriers located adjacent the bucket, for stopping the bucket in both its loaded and unloaded positions.

4. In a material handling apparatus, a pair of opposing carriers, a conveyer bucket pivotally mounted between said carriers, and a bar between the carriers located ad-

jacent the bucket for stopping the bucket in both its loaded and unloaded positions, and arranged as a distance piece between said carriers.

5. In a material handling apparatus, a pair of opposing carriers, a conveyer bucket pivoted between said carriers, means for tripping the bucket, and means intermediate the ends of the bucket and connecting said carriers for stopping the bucket in both its loaded and unloaded positions.

6. In a material handling apparatus, a bucket adapted to tilt in one direction only and discharge while moving in a non-horizontal plane, means for tilting and discharging the bucket, and means connecting the carriers of said bucket for stopping the bucket in both its loaded and unloaded positions.

7. In a material handling apparatus, a bucket adapted to tilt and discharge while moving in a non-horizontal plane, means for tilting and discharging the bucket, and means connecting the carriers of said bucket intermediate the ends of the bucket for stopping the bucket in both its loaded and unloaded positions.

8. In a material handling apparatus, a pivoted conveyer bucket adapted to tilt and discharge while moving in a non-horizontal plane, means for stopping the bucket in both its loaded and unloaded positions, means on said bucket for tripping the same, said stopping means connecting the carriers of said bucket, and a pivoted trip lever mounted adjacent the point of travel, for engaging said tripping means.

9. In a material handling apparatus a pivoted conveyer bucket adapted to tilt and discharge while moving in a non-horizontal plane, means on said bucket for tripping the same, means for stopping the bucket in both its loaded and unloaded positions, and a pair of trip levers mounted on a cross shaft adjacent the point of travel for engaging said tripping means, said stopping means connecting the carriers of the bucket.

10. In a material handling apparatus, in combination, a carrier composed of a pair of chains each comprising a plurality of link sections such link sections each having one bifurcated end and one single or plain end, means for engaging said ends of adjacent sections together, said sections being provided intermediate their ends with means for the reception of trunnions for supporting swinging carrier members, and means carried by said chains adjacent said means on the ends of said sections for stopping the buckets in both their loaded and unloaded positions.

11. In a material handling apparatus in combination, a carrier composed of a pair of chains each comprising a plurality of link sections, such link sections having in-

terengaging ends whereby lateral movement of each link section relatively to its adjacent link section is prevented, means for pivotally connecting said ends of adjacent sections, said sections being provided intermediate their ends with means for the reception of trunnions for supporting swinging carrier members, and means carried by said chains adjacent said means on the ends

of said sections for stopping the buckets in 10 both their loaded and unloaded positions.

In testimony whereof I have hereunto signed my name in the presence of the two subscribed witnesses.

WILLIAM THOMAS JAMES.
